UNITED STATES PATENT OFFICE.

JAMES GEDDES, OF WINNIPEG, MANITOBA, CANADA.

ATTACHMENT FOR VEHICLES.

1,199,885.

Specification of Letters Patent.

Patented Oct. 3, 1916.

Application filed December 24, 1914. Serial No. 878,900.

To all whom it may concern:

Be it known that I, JAMES GEDDES, of the city of Winnipeg, in the Province of Manitoba, Canada, have invented certain new and useful Improvements in Attachments to Vehicles, of which the following is the specification.

The invention relates to improvements in attachments to vehicles and the principal object of the invention is to provide an attachment to a vehicle which when in use will effectively prevent a restive animal from wandering or running away when left by the driver.

A further object of the invention is to provide an effective device of the above class which can be manufactured at small cost and readily applied to existing types of vehicles.

A still further object of the invention is to provide an attachment by the use of which the driver can stop his horse in event of being unable to control him by the reins.

A still further object of the invention is to provide an attachment for the above purpose which remains as a permanent fixture on the vehicle and cannot accordingly be easily stolen and is at all times ready for use.

With the above objects in view the invention consists essentially in a rotatably mounted shiftable drum carried by the vehicle adjacent one of the rear wheels, a pinion in connection with the drum, a gear wheel secured to the rear wheel, means controlled by the driver for controlling the drum and effecting the engagement or disengagement of the pinion with the gear wheel and a cable wound on the drum and provided with a suitable snap hook, the parts being arranged and constructed as hereinafter more particularly described and later pointed out in the appended claim.

Figure 1 represents a side view of the attachment applied on a vehicle. Fig. 2 represents a plan view of the same. Fig. 3 represents an enlarged detailed rear view of the drum and associated parts as they appear on the back axle. Fig. 4 represents a plan view of the parts appearing in Fig. 3. Fig. 5 represents a horizontal sectional view through the standards and parts carried thereby, the section being taken in the plane denoted by the line X-X' Fig. 3.

In the drawings like characters of refer-

ence indicate corresponding parts in each figure.

1 represents a wagon box provided with the usual driver's seat 2 and carried by rear springs 4 and 5 and a front spring 6, these being mounted on the front and rear vehicle axles 7 and 8 in the usual way. The axles are carried by sets of front and rear wheels 9, 9', 10 and 10'.

11 represents the usual reach between the axles and 12 represents the shafts connected to the front axle. A horse is shown as hitched to the shafts.

My invention is now described:

13 represents a saddle or base plate secured to the rear axle 7 between the spring 5 and the wheel 10 the fastening being made by means of U-bolts 14 and 15 supplied with nuts 16.

The saddle is preferably cast with two upright standards 17 and 17', the standards being supplied at their upper ends with opposing alined bearings 18 and 19 which carry rotatably a spindle 20 arranged also to shift endwise. On the spindle I have mounted a drum 21 keyed or otherwise secured thereto and to the drum I fasten a winding cable 22 which extends forwardly and is guided by suitable eyes applied on the vehicle and terminates in a snap hook 23 designed to be snapped into or attached to the bit ring 24.

The spindle carries a pinion 25 designed in the shifting of the spindle to engage with the gear wheel 26 permanently secured in any suitable way to the wheel 10.

The standard 17 carries an outstanding arm 27 which carries a pivoted lever 28 having the lower end connected by a link 29 to one arm of a pivoted bell crank 30 suitably suspended by brackets 31 from the standard 16. The upper end of the lever is slotted and receives a pin 32 extending from a shank 33, the shank being connected by means of a ball and socket joint 34 with the adjacent end of the spindle.

35 is a link connecting the bell crank with the lower end of a hand lever 36 pivotally secured at 37 to the side of the wagon box in a location convenient to the driver on the seat. The lever is supplied with the customary hand latch 38 and detent 39, the detent operating over a quadrant 40 secured to the wagon box.

In connection with the hand lever I wish

it to be noticed that it is only provided with two adjustments, that is, the quadrant is fitted with two notches to receive the detent. In the forward position of the lever the pinion is disengaged from the gear wheel and in the back position it is engaged. Accordingly one can tell immediately by looking at the lever whether or not the pinion is in or out of engagement.

10 Under normal conditions, or when one is driving, the lever is in the position shown in Fig. 1 of the drawings, that is, the pinion is out of engagement with the gear wheel. The snap hook however is connected to the 15 ring of the bit. Accordingly the horse's head is entirely free of any pulling action due to the attachment.

Upon the driver leaving the vehicle he 20 throws the lever backwardly to engage the pinion with the gear wheel and he can then leave the animal, satisfied that he cannot move to any extent without setting the attachment into operation. It is obvious that 25 if the animal should attempt to advance the gear wheel attached to the rear wheel will operate the pinion in a direction such that the drum will wind the cable with the result that the cable will pull on the animal's head and arrest him. Upon the driver returning 30 to the vehicle he has simply to move the lever to the original position to disengage the pinion from the gear wheel. This immediately frees the animal's head as will readily be understood.

35 I wish to point out that the action of the drum is what might be termed a gradual one and will not accordingly when operating have a tendency to unduly scare a restive horse.

40 From the above description it will be seen that the attachment is at all times on the vehicle and is always ready for use and re-

quires but little action on the part of the driver.

While I have shown a particular construction for shifting the spindle by the movement of the hand lever still I wish it to be understood that various other mechanical arrangements for accomplishing this object could be readily supplied without in the least departing from the spirit of this invention, the salient feature of which resides in the provision of a winding drum designed to be operated in winding by one of the vehicle wheels and connected by a cable or such like 55 to the head of the animal attached to the vehicle, the winding action of the drum being controlled by the driver from the seat.

What I claim as my invention is:—

An attachment to vehicles for arresting an 50 animal hitched thereto comprising a saddle permanently secured to the rear axle and adjoining one of the rear wheels, said saddle being provided with a pair of upstanding standards, a spindle rotatably mounted in 55 the standards and shiftable endwise in the same, a drum permanently mounted on the spindle, a cable secured to the drum and connected with the head of the animal, a gear wheel permanently secured to the said 70 rear wheel, a pinion permanently secured to the end of the spindle next the gear wheel and normally disengaged from the gear wheel and means controllable from the vehicle seat for shifting the spindle and engaging the pinion with the gear wheel, as and for the purpose specified.

Signed at Winnipeg this 27th day of August, 1914.

JAMES GEDDES.

In the presence of—

GERALD S. BOXBURGH,
ROLAND FOSTER.
